UNITED STATES PATENT OFFICE.

CHARLES A. TATUM, OF NEW YORK, N. Y., ASSIGNOR TO WHITALL, TATUM & CO., OF SAME PLACE.

DESIGN FOR A BOTTLE OR JAR COVER.

SPECIFICATION forming part of Design No. 18,005, dated January 3, 1868.

Application filed December 1, 1867. Serial No. 256,724. Term of patent 7 years.

To all whom it may concern:

Be it known that I, CHARLES A. TATUM, residing in the city, county, and State of New York, have invented and produced a new and original Design for a Bottle or Jar Cover, of which the following is a specification, reference being had to the accompanying drawing, forming part hereof, in which the figure is a side elevation of my newly-designed cover in position on a jar.

A represents a jar or bottle of suitable outline.

B is the cover, which is in the main dome-shaped. On the lower part of the cover B are

a series of ribs or corrugations, b. On the top 15 of the dome-shaped cover B is an acorn-like ornament, D.

I claim—

The design for a jar or bottle cover herein described, the same consisting of the dome-shaped body B, having ribs or corrugations b, and the acorn-like ornament D on top of said dome, substantially as shown.

C. A. TATUM.
